UNITED STATES PATENT OFFICE.

ARCHIBALD H. DAVIS, OF LINCOLN, NEBRASKA.

SASH, DOOR, OR STORE-FRONT CONSTRUCTION.

Application filed February 23, 1928 Serial No. 256,433.

The present invention relates to sash, door, or store front construction and embodies novel features, constructions, and combinations differing from the disclosures of my 5 Patent 1,550,430, August 18, 1925, and pending application Serial No. 145,824, filed November 2, 1926.

The object of the invention is to provide improved front and rear mouldings, co-operating in a novel manner to enable them to grip, and securely hold, a pane of glass of any thickness without danger of breakage of the pane and with adaptability for ready assembly, cutting to the proper length, and 10 durability and firmness of grip and, further, for installation without requiring jambs or stops and, also, if used as the frame for a door, without necessitating the employment of a slam strip.

20 In my Patent 1,550,430 I have disclosed front and rear sections or mouldings fulcrumed on each other and adapted to be relatively tensioned but in that construction the outer moulding or section must be dropped in 25 between the pane and the upwardly extending front part of the rear section before the front section can be tensioned to grip the pane; furthermore, in my patented construction aforesaid, the manner in which the outer 30 section is fulcrumed on the rear or inner section, provides a joint which, under some circumstances, might collect water due to the "elements" and used in washing the pane with possibility of freezing, and in the patented construction some little difficulty has 35 been experienced in "finding" the screw holes in the outer section because they lie back of the upwardly extending front part of the rear section.

40 While the present invention is not intended to be strictly limited to embodiments in relatively heavy extruded inner and outer sections, nevertheless it is peculiarly adapted for embodiments in heavy extruded sections because relatively heavy extruded sections afford strength, durability, and firmness of grip on the pane far in excess of that obtainable with sheet metal stamped or shell sections. Therefore, in describing the invention, the use of extruded metal is emphasized, although it is not intended to limit the construction to extruded metal unless specified in the claims.

45 In the present construction the front or outer moulding or section is fulcrumed on the rear or inner moulding or section in a novel manner and combined with a new friction or braking joint which prevents too great pressure from being exerted against the pane when the tension screws are tightened and, 60 also, securely anchors the outer section or moulding, although it is fulcrumed for adjustment within a relatively wide range to grip panes ranging in thickness from about one-sixteenth to about one-half inch and yet 65 there is no possibility of the outer moulding or section becoming displaced vertically in relation to the rear section.

70 Another feature of the present improvements is that the outer moulding or section lies outside of the rear moulding or section instead of being partly contained within the rear moulding as in my Patent 1,550,430. This arrangement has several advantages, among which are, the tension screws, first 75 passing through the outer moulding, more easily "find" the holes in the upright portion at the front of the back section and, also, no exposed joint exists to collect the water, with possibility of freezing in cold weather; still 80 further, the outer and inner sections of the moulding can be assembled at the factory with greater ease and cut off to the proper length at the point of installation.

85 Those portions of the inner and outer mouldings or sections which are intended to directly contact with the pane are rounded so that no square or sharp part is presented to the pane, hence danger of cracking or breaking of the pane is minimized when tension is applied to the moulding and when wind, vibration, etc. rock or vibrate the pane or the parts of the moulding.

90 It is unnecessary to provide the conventional store front jamb or stop when the present moulding is used in store front setting. When the construction is employed as a pane holding means for a door, it is not necessary to use a "slam" section in connection therewith but when used on a swinging 100 casement window, the construction is well adapted to be combined with a slam strip or section.

105 In my pending application Serial No. 145, 824, aforesaid, provision is made for relative flexibility as between the front and rear sections. The present construction may have this function and in that respect embodies improvements over the construction shown in said application.

Those embodiments of the invention which are hereinafter described and which appear in the drawings are some of the principal forms the invention may assume but it is to be understood that other embodiments will fall within the principle of the invention.

In the accompanying drawings:

Figures 1, and 2, respectively represent the outer and rear sections, to afford a clear understanding of their cross sectional shapes;

Fig. 3, is a vertical section showing the construction applied to a pane, as used on a casement window in connection with a "slam" section;

Fig. 4, is a vertical section showing the manner in which the improvements may be embodied in a frame for a door, also illustrating by full and dotted lines, the adjustability of the outer section to accommodate panes of different thicknesses, it being understood that the tension screws are used, though not shown;

Fig. 5, is a sectional perspective view showing the construction on a store front with gutter and drainage holes;

Fig. 6, is a detail fragmentary view showing the fulcrum and sliding friction joint of the form shown in Figs. 5 and 9;

Fig. 7, is a sectional perspective view illustrating another modification;

Fig. 8, illustrates how the rear moulding may be provided with ears for the attachment to the outer section to afford additional flexibility;

Fig. 9, is a vertical section showing the form of Fig. 8 applied to a pane; and

Fig. 10, illustrates another modification wherein the front of the rear section comprises supplemental pieces constituting clips which may be of any desired thickness to afford the desired flexibility, when flexibility is required.

While the front part of the rear moulding may be made as supplemental clips, as shown in Fig. 10, nevertheless the construction comprises a front moulding 1 and a rear moulding 2.

Referring first to Figs. 1, 2, 3, 4, the mouldings 1 and 2 are of relatively heavy extruded metal and, as shown in Fig. 3, they are tensioned by screws 3 at different points of the length thereof, only one being shown. The sections 1 and 2 have inclined upper parts which are provided with curved or rounded surfaces 4, 5 where they are adapted to engage the pane 6. Thus, no sharp edge or square shoulder engages the glass pane 6 and liability of cracking or chipping from undue pressure or vibration or movement due to the wind or any cause, is prevented.

The sections 2 may be provided with a gutter 7 as shown in Figs. 5, 7, 8, 9, 10, if the installation requires a gutter and drainage. If the gutter is provided, holes 8 at different

points of the length of the moulding 2 will be provided as illustrated in Fig. 5 and the front of the moulding 2 and of the moulding 1 will have drainage holes 9 so that the water entering the moulding will pass to the exterior of the installation.

The manner in which the section 1 is fulcrumed on the front of the section 2 and frictionally seated thereon, represents improvements over the fulcrumed construction found in my Patent 1,550,430. However, as shown by contrast in Figs. 3, 6, 7, for instance, the principle in that respect may be embodied in forms differing in detail.

In Figs. 1, 2, 3, 4, the section 2 is provided with a front wall 10 which is spaced in advance of the pane 6 to a suitable extent to permit of the functions hereinafter described and which has a square shoulder 11. The upper edge of the front wall 10 is rounded from front to rear as shown at 12.

The section or moulding 1 has a knife edge or fulcrum 13 which engages the shoulder 11 and fulcrums on said shoulder as shown in Figs. 3 and 4. The clearance illustrated at 14 is such that a very considerable swinging movement of the section 1 is possible so that a pane of glass varying from one-sixteenth to one-half inch in thickness may be accommodated and gripped between the parts 4 and 5.

The section 1 is provided with an arc-shaped inner surface 15 which is struck on substantially the same arc as that of the surface 12, said surfaces being in contact and constituting a combined retainer and friction brake 1, in connection with the fulcrum 13 and shoulder 11 serving the following purposes. Regardless of how tight the screws 3 are drawn up, a frictional checking action is brought about between the surfaces 12 and 15 which prevents undue pressure being exerted on the pane 6. Also, the section 1 is interlocked with the front wall 10 in such manner that the tension exerted by the screws 3 cannot cause vertical displacement of the section 1. The clearance space 16 between the section 1 and the front wall 10 permits the swinging or tilting movements illustrated in Fig. 4 so that panes of different thicknesses may be accommodated.

Differing from the relative arrangement of front and rear mouldings shown in my Patent 1,550,430, the lower part of the section 1 lies outside of the front wall 10 of the section 2 so that an unbroken surface is provided on the exposed part of the moulding and no joint exists in which water can accumulate and freeze during cold weather. Furthermore, by reason of the section 1 being located outside of the front wall 10, and the screws 3 passing through section 1, it is much easier for the screws to "find" the screw threaded holes 17 in the front wall 10 and assembly is

easier and also the moulding is rendered self-contained and can be more easily cut off and set up where it is to be installed.

In Fig. 3, the construction is shown in connection with a casement window whose frame appears at 18 and there may be provided a "slam" piece 19, whereas in Fig. 4, when the construction is embodied in a door or sash, the sash or door frame 20 alone is used, as 10 no slam strip is necessary.

In Fig. 5, where the construction is combined with a sill 21 and a stop 22, any suitable fastening means 23 may be used for securing the section 2 to the sill. The condensation gutter 7 may be employed, as previously described. In lieu of the knife edge or fulcrum 13, the form of the invention shown in Figs. 5 and 6 is provided with a bead or edge 24 whose surface is of general 20 circular shape and which has contact with the walls of the shoulder 11 at the points 25, 26. The resultant effect is the same as with the construction shown in Figs. 1 to 4.

As shown by dotted lines 27, Fig. 1 and full 25 lines 27, Figs. 5, 6, 7, 9, 10, the under surface of the horizontal part of the section 1 is inclined when the construction is intended for use in connection with a sill or the like because this is necessary in order to afford 30 the requisite clearance required by different positions of adjustment of the section 1 according to the thickness of the pane 6 and to facilitate adjustment under any circumstances.

35 In the construction shown in Fig. 7, in lieu of the square shoulder 11, on the front wall 10 of the section 2, there is provided a concaved shoulder 28 for the bead-like fulcrum 24. Furthermore, instead of the upper 40 edge of the front wall 10 being struck on the arc of a circle corresponding to the curve 15, the said upper end of the front wall 10 is bevelled as shown at 29 which facilitates the drawing together of the sections 1 and 2 by 45 the screws 3. At the same time, the general frictional effect previously described, is obtained in this modification.

In Fig. 9, the dotted lines 30 illustrate how the front wall 10 of the section 2 may have a 50 certain amount of adaptability to flex. This is accomplished by the use of spaced lugs or ears 10' as shown in Fig. 8, instead of employing a continuous front wall 10 for the section 2. Each of these lugs 10, or as many 55 of them as may be found to be necessary, are provided with screw holes 17' for the accommodation of the tension screws 3.

60 In Fig. 10, there is illustrated a modification embodying the general construction shown in Figs. 5 and 6 but with an added feature.

There are flexible clips 31 secured by fastenings 32 to the bottom of the section 2 and provided with screw threaded holes similar

to the holes 17', for engagement by the 65 screws 3. These clips have a re-bent part 33 which, in connection with the front edge of the bottom of the section 2, constitute a shoulder 11' similar to the shoulder 11. The upper part of the clip has a curved top surface 34 for engagement with the curved face 15 of the section 1. The clips 31 afford a certain amount of flexibility, enabling the pane 6 to be gripped somewhat more elastically than in the constructions heretofore 75 described.

It will be understood, however, that I do not limit myself to clips 31 which are of the relatively thin construction illustrated, as they may have the same thickness as the 80 lugs 10'.

What I claim is:

1. In a sash, door, or store front construction, the combination with a rear section, of a front section whose lower part is fulcrumed 85 on the rear section, and having its upper part adapted to bear on the pane, the intermediate part of the front section being adapted for a sliding, braking, contact with the rear section.

2. In a sash, door, or store front construction, the combination with a rear section, having a front part, of a front section whose lower part is fulcrumed on the front part of the rear section, and having its upper part 90 adapted to bear on the pane, the intermediate part of the front section being adapted for a sliding, braking contact with the front part of the rear section.

3. In a sash, door, or store front construction, the combination with a rear section, of a front section whose lower part is fulcrumed 100 on the rear section, and having its upper part adapted to bear on the pane, the intermediate part of the front section being adapted for a sliding, braking, contact with the rear section, and tensioning means connecting the front section to the rear section intermediate 105 the aforesaid fulcrum and sliding, braking contact.

4. In a sash, door, or store front construction, the combination with a rear section, having a front part, of a front section whose lower part is fulcrumed on the front part of the rear section, and having its upper part 115 adapted to bear on the pane, the intermediate part of the front section being adapted for a sliding, braking contact with the front part of the rear section, and tensioning means connecting the front section to the front part of the rear section intermediate the aforesaid fulcrum and sliding, braking contact.

5. In a sash, door, or store front construction, the combination with a pane-receiving rear section adapted to bear on the pane and provided with a front part, of a front section 125 adapted to bear on the pane and which lies outside of, and covers, the aforesaid front part of the rear section, said front section be-

ing fulcrumed on the rear section and also having a sliding, braking contact with the front part of the rear section.

6. In a sash, door, or store front construction, the combination with a pane-receiving rear section adapted to bear on the pane and provided with a front part, of a front section adapted to bear on the pane and which lies outside of, and covers, the aforesaid front 10 part of the rear section, said front section being fulcrumed on the rear section and also having a sliding, braking contact with the front part of the rear section, and tensioning means for the front section.

15. 7. In a sash, door, or store front construction, the combination with a pane-receiving rear section adapted to bear on the pane and provided with a front part, of a front section adapted to bear on the pane and which lies 20 outside of, and covers, the aforesaid front part of the rear section, said front section being fulcrumed on the rear section and also having a sliding, braking contact with the front part of the rear section, and tensioning 25 means connecting the front part of the rear section to the front section.

8. In a sash, door, or store front construction, the combination with a pane-receiving rear section adapted to bear on the pane and 30 provided with a front part, of a front section adapted to bear on the pane and which lies outside of, and covers, the aforesaid front part of the rear section, said front section having its lower part fulcrumed on the rear

section, and its intermediate part provided with a braking surface overlying and slidably contacting with the front part of the rear section.

9. In a sash, door, or store front construction, the combination with a pane-receiving rear section adapted to bear on the pane and provided with a front part, of a front section adapted to bear on the pane and which lies outside of, and covers, the aforesaid front 40 part of the rear section, said front section 45 having its lower part fulcrumed on the rear section, and its intermediate part provided with a braking surface overlying and slidably contacting with the front part of the rear section, and tensioning means connecting the 50 front and rear sections intermediate the aforesaid fulcrum and slideable braking means.

10. In a sash, door, or store front construction, the combination with a rear section having a front part, of a front section located in front of said front part of the rear section and fulcrumed thereon and also having a braking contact with the said front part, there being provided a space between the said 55 front part of the rear section and the said front section below the braking contact aforesaid, which permits the front part of the rear section to flex without detracting from the action of the front and rear sections. 60 65

In testimony whereof I affix my signature.

ARCHIBALD H. DAVIS.
